US00D708033S

(12) **United States Design Patent**
Bohanan

(10) **Patent No.:** **US D708,033 S**
(45) **Date of Patent:** **** Jul. 1, 2014**

(54) **PAINT STIRRING DEVICE**

(71) Applicant: **Robert Bohanan**, Normal, IL (US)

(72) Inventor: **Robert Bohanan**, Normal, IL (US)

(**) Term: **14 Years**

(21) Appl. No.: **29/472,205**

(22) Filed: **Nov. 9, 2013**

(51) LOC (10) Cl. **08-03**

(52) U.S. Cl.

USPC **D8/70**; D8/14; D7/412

(58) **Field of Classification Search**

USPC D7/99, 306–313, 317–318, 326, 356, D7/376–386, 392, 397–399, 412–415, 607, D7/665, 688, 693; D8/14; D15/12, 28, D15/138; D32/35, 46, 54; 7/105, 170, 99/348, 509–511; 241/101.1, 241/274–278.2, 282.2, 285.1–285.3, 291, 241/292.1; 366/64–67, 98, 129, 192, 366/197–211, 251, 270, 279–292, 312, 366/327.3, 343, 605
